UNITED STATES PATENT OFFICE

ROY H. LEDBETTER, OF FAIRFIELD, ALABAMA

FIN NOSED TUYÈRE

Application filed November 12, 1928. Serial No. 318,757.

This invention relates to improvements in blast furnace tuyères and aims to provide a tuyère so constructed that the useful life of the tuyère is greatly prolonged.

Heretofore, tuyères have been formed with various kinds of refractory coatings and linings in the nose portions thereof. In practice, it has been found, however, that in a short length of time, the refractory materials had fused with furnace slag or are frequently broken by falling particles and the metallic parts of the tuyère are exposed to the destructive action of the furnace burden and frequent replacements are necessitated.

My improved tuyère overcomes these objections and provides an article which practice has shown has greatly increased life over tuyères heretofore used and the tuyère can be produced at a comparatively small cost as compared with tuyères having refractory linings and the like.

An embodiment of the invention is illustrated in the accompanying drawing, where-

in—

Fig. 1 is a longitudinal section exemplifying one embodiment of the invention;

Fig. 2 is a view from the right side of Fig. 1.

Referring in detail to the drawing, the tuyère consists of a copper casting having an outer annular shell 10, an inner shell 12, an outer end wall 14 and an inner end wall 16 forming a chamber 18 adapted to have a cooling medium such as water circulated therethrough. The outer wall 14 is provided with threaded openings 20 and 22 for the reception of pipes for circulating the cooling medium.

At the end of the tuyère which is adapted to project into the blast furnace, I provide a plurality of spaced annular longitudinally extending ribs 24, these ribs are cooled by water in the chamber and thus provide an end of the tuyère which resists the temperature within the furnace. The ribs will be burned off slightly on their exposed edges

until they become so short that the cooling effect of the water balances the heating effect of the gases within the furnace, after which they will remain as a permanent protection to the end of the tuyère. They are placed so close together that they protect the end wall 16 from excessive heating. These projecting cool ribs also intercept the hot dripping iron and thus serve to protect the wall 16 against the destructive action of such hot metal.

While I have shown in the drawing only three fins and while these have been shown of circular or annular form, it is to be understood that a greater or fewer number of fins may be used and that instead of being annular in form, they may be corrugated or zig-zagged so as to provide an extended heat dissipating surface.

Various other modifications may be made by those skilled in the art without departure from the invention as defined in the appended claims.

What I claim is:—

1. A blast furnace tuyère comprising a metallic body having a cooling chamber formed therein and having a nose portion comprising a plurality of fins with open spaces between them extending beyond the end of the cooling chamber.

2. A blast furnace tuyère comprising a metallic body having a cooling chamber formed therein and having a nose portion comprising a plurality of annular fins with open spaces between them extending beyond the end of the cooling chamber.

3. A blast furnace tuyère comprising a hollow copper body having a plurality of longitudinally extending integral fins with open spaces between them formed on the inner end of the tuyère body.

4. A blast furnace tuyère comprising a metallic body having a cooling chamber formed therein and having a nose portion comprising spaced fins extending beyond the

end of the cooling chamber with open spaces between said fins.

5. A blast furnace tuyère comprising a metallic body having a cooling chamber formed therein and having a nose portion comprising an outer annular fin, an inner annular fin and intermediate fin separated from the outer and inner fins by open spaces.

In witness whereof, I have hereunto signed my name.

ROY H. LEDBETTER.
